UNITED STATES PATENT OFFICE.

FREDERICK T. MOORE, OF EAST HARTFORD, AND CHRISTIAN PFEIFFER, OF HARTFORD, CONNECTICUT, ASSIGNORS TO COLT'S PATENT FIRE ARMS MANUFACTURING COMPANY, OF HARTFORD, CONNECTICUT, A CORPORATION OF CONNECTICUT.

GUN MOUNT.

Application filed June 21, 1926. Serial No. 117,528.

This invention relates particularly to gun legs so as to be capable of movement about vertical and horizontal axes. Carried by the 55 leg 2 is a seat 4 and carried by the legs 3, 3 are foot rests 5, 5.

5 its use to guns of any one type.

One of the objects of the invention is to provide a gun mount having improved means for absorbing and dissipating the shock and vibration which frequently occur 10 as the result of the recoil action of a gun particularly of a rapid fire automatic gun.

Another object of the invention is to provide improved means for making the gun mount more rigid than has heretofore been 15 deemed possible, this being accomplished without interfering with any of the ordinary adjustments.

Still another object of the invention is to provide a gun mount having adjustable 20 stops for limiting the adjustment of the mount to elevate or depress the gun.

Still further objects of the invention will be apparent from the specification and claims.

25 In the accompanying drawings, we have shown the embodiment of the invention which we now deem preferable but it will be understood that the drawings are merely for purposes of illustration and are not to be 30 considered as defining or limiting the scope of the invention, the claims forming a part of the specification being relied upon for that purpose.

Of the drawings:

35 Fig. 1 is a side view of a gun mount embodying the invention, together with a gun carried thereby.

Fig. 2 is a perspective view of the gun mount with the legs thereof omitted, this 40 view being taken in a diagonally downward direction.

Fig. 3 is a central longitudinal sectional view through the gun mount.

45 Fig. 4 is a fragmentary sectional view similar to Fig. 3, but with the section taken immediately behind the right hand side plate of the cradle.

Referring to the drawings, particularly Fig. 1 thereof, 1 represents the main cradle 50 by means of which the gun is indirectly supported. The cradle is carried by ground engaging legs 2, and 3, 3 and in accordance with the customary practice it is preferably adjustably supported with respect to the

Fig. 3 clearly shows the vertical pivotal connection between the cradle 1 and the legs 2, and 3, 3. As illustrated there is a pivot 60 base 6 to which the legs are pivotally attached in the usual manner. A swivel base 7 carrying the cradle 1 is supported on the pivot base 6 and the said pivot base and swivel base are provided respectively with 65 complementary pivot and bearing portions which permit the said pivotal movement. Preferably and as shown, the pivot base 6 is provided with a vertical stud 8 and the swivel base 7 is provided with a bearing 70 aperture which receives and fits the stud so as to provide a pivotal bearing for the swivel base and the parts carried thereby. A shoe 9 is adjustably mounted in a recess in the swivel base adjacent the said aperture 75 and it is provided with a tongue which projects into an annular groove 10 in the stud 8. The engagement of the tongue with this groove prevents the pivot base and the swivel base from being accidentally separated. A screw 11 operable by a handle 12 is provided for forcing the shoe 9 against the stud 8 to thus clamp the swivel base 7 80 against pivotal movement with respect to the pivot base 6.

85 Preferably and as illustrated, the cradle 1 comprises two similar parallel side plates 13, 13 which are spaced apart and located at opposite sides of the swivel base 7. In order that the cradle may be horizontally pivoted 90 as aforesaid, a pivot pin 14 is provided which extends through a horizontal aperture in the upper part of the pivot base and near the vertical pivotal axis. This pin also extends through apertures in two side plates, 95 thus providing a pivotal support for the cradle. Tie members extend transversely between the side plates 13, 13, these being shown at 13a.

For the purposes of clamping the cradle in 100 any desired position of adjustment with respect to the swivel base 7, there is provided a horizontal clamp rod 15 which extends through a suitable aperture in the swivel base 7 and which is provided at the left-hand end with a head adapted to engage the left-hand side plate 13 and at its right- 105

hand end with a nut 16 adapted to engage the right-hand side plate 13. A handle 17 is provided for returning the nut 16 and forcing both the head and the nut into firm 5 frictional engagement with the corresponding side plates. In this way the cradle may be clamped and held against movement about its horizontal pivotal axis.

The construction as thus far described is 10 well known and does not of itself constitute any part of our present invention.

In Figs. 1 and 3 we have shown a gun G which is carried by the mount. This gun does not of itself constitute any part of the 15 invention and for purposes of illustration we have shown a gun similar to that shown in the patent to John M. Browning, No. 1,293,021, dated February 4, 1919. The gun G is not mounted directly on the cradle, as 20 has been the practice prior to our invention, but it is mounted upon a saddle 18 which is supported by the cradle and which is longitudinally slidable with respect thereto.

The details of construction of the saddle 25 may be varied but we prefer and have shown a saddle comprising two side plates 19, 19 which are respectively located adjacent the corresponding side plates of the cradle. The two side plates are connected by suitable 30 cross members, two cross bars 20 and 21 being shown. Each of the side plates 19, 19 is preferably provided with longitudinal grooves 22 and 22^a into which project two shoes 23 and 24, which are carried by the 35 saddle. Preferably two pins 25 and 26 extend transversely between the two side plates 13, 13 of the cradle, and the side plates 19, 19 of the saddle are longitudinally slotted to receive the said pins. These pins are 40 utilized for supporting the before-mentioned shoes 23 and 24. By means of this construction the saddle is so supported as to be capable of longitudinal movement on the cradle, the said shoes 23 and 24 providing a 45 broad bearing surface for supporting the saddle and guiding the longitudinal movement thereof.

Provision is made for detachably connecting the gun to the saddle in such a way that 50 it is entirely supported thereby. The gun attaching means may be constructed in accordance with customary practice and as shown it comprises two pins 27 and 28 which are adapted to extend through aligned holes 55 in the two side plates 19 and also through suitable apertures provided for the purpose at the lower part of the gun G.

In the operation of a gun of the type 60 illustrated, the major portion of the energy of recoil is absorbed and utilized within the gun, there being very little tendency for the gun as a whole to recoil or vibrate longitudinally. However, under some circumstances there may be a slight longitudinal bodily re- 65 coil movement or vibration of the gun dur-

ing operation and with the construction illustrated it will be apparent that the saddle 18 by reason of its slidable mounting will partake of any such bodily recoil movement. In order that this bodily recoil movement may be absorbed and dissipated without being transmitted to the main body of the mount to any considerable extent, we provide a spring for resisting the longitudinal movement of the saddle and thereby resisting the 70 longitudinal movement of the gun. The spring may vary as to construction and as to mounting, but we prefer and have shown a coil spring 29 which is interposed between the cross bar 20 and the pin 26. Preferably the spring 29 is supported and held in place by a tube 30 which extends through apertures in the cross bar 20 and the pin 26. As illustrated the spring 29 bears at one end directly against the cross bar 20 and at the other end against a collar 31 pinned to the tube 30 and bearing against the pin 26.

It will be understood that immediately after any recoil movement which compresses 90 the spring 29 the said spring will react and return the saddle and the gun to their normal positions. In order to limit this return movement and to absorb any shock resulting therefrom, we preferably provide a second 95 spring 32 which acts in opposition to the spring 29. Preferably the spring 32 is a coil spring similar to the spring 29 and also mounted upon the tube 30 which is extended rearward for this purpose. One 100 end of the spring 32 engages a collar 33 pinned to the tube 30 and the other end engages a collar 34 which is loosely mounted on the tube 30.

As already described elevational adjustment of the gun may be effected by moving the saddle about the pivot pin 14, the saddle being locked in this position by means of the handle 17 and the parts associated therewith. We prefer however to provide additional means for providing a more delicate elevational adjustment of the gun, and to this end the saddle 18 is made angularly adjustable with respect to the cradle. As shown and as preferred the adjustment is 110 effected about the pin 25 as a pivot and the pin 26 is utilized for the purpose of vertically moving the shoes 24 to bring about the adjustment. As shown the pin 26 is in the form of a yoke which is connected to or formed integrally with a downward extending screw 35. A combined nut and hand wheel 36 has a threaded engagement with the screw and the outer portion or hub of the member 36 is threaded to engage a nut 37. The nut 37 is provided with trunnions 38 which project through apertures in the side plates 13, 13, thus providing a pivotal support for the nut. Preferably the threads of the member 36 are oppositely inclined so 120 125 130

that when the hand wheel is turned the screw 35 is given a longitudinal movement which is the resultant of the combined action of the two sets of threads. The construction described makes it possible, by turning the hand wheel, to raise or lower the shoes 24 and thus raise or lower the outer or rear portions of the saddle and the gun. It will be apparent that inasmuch as the elevational adjustment is effected by moving the shoes it does not in any way interfere with the longitudinal movement of the saddle which has already been described.

In order to prevent any vibration of the gun or any inaccuracy of firing due to lost motion between the relatively movable parts of the cradle and saddle, we preferably provide spring means for applying vertical pressure to the saddle. As preferred and as illustrated there are two tension springs 39, 39 which are connected at their upper ends to a pin 40 extending transversely between the side plates 19, 19 of the saddle 18. The springs 39, 39 are connected at their lower ends to a pin 41 extending transversely between depending brackets secured to the side plates 13, 13 of the cradle 1.

Preferably in order to more firmly support the swivel base 7 on the pivot base 6, we provide the said pivot base and swivel base with complemental segmental bearing surfaces which are concentric with the vertical pivotal axis but which are independent of and spaced from the primary bearing surfaces at the stud 8. As illustrated the pivot base 6 is provided with a rearward extension 42 on which is formed a segmental conical bearing surface 43. The swivel base 7 is similarly formed with a rearward extension 44 having a segmental bearing surface 45 shaped and positioned to engage the surface 43. It will be seen that the bearing surfaces 43 and 45 by reason of their engagement provide a support for the swivel base which is relatively close to the center of gravity of the overhanging parts of the mount and of the gun.

Preferably in order to make still further provision for rigidly supporting the overhanging parts of the cradle we provide at least one, and ordinarily two, links 46 and 47. These links are horizontally pivoted to the extension 44 of the swivel base and the cradle is provided with means which engage the links and permit them to slide longitudinally when the cradle is adjusted about the pivot pin 14. Provision is made, however, for locking the links in fixed relation to the cradle when desired, thus enabling the links to act as supporting braces. Preferably the links are longitudinally slotted and a transverse clamping bolt 48 extends through apertures in the side plates 13, 13 and through both of the slots. This clamping bolt 48 is provided with a head 48^a at one end and with a nut 49 at the other end, the nut 49

having a handle 50 whereby it may be turned. It will be obvious that by turning the handle 50 the two links 46 and 47 may be drawn toward each other and into firm clamping engagement with the side plates 13, 13.

For some classes of operation in warfare it is desirable to provide definite limits of elevation and depression which can not be accidentally or unintentionally passed by the gun operator in his manipulation of the gun. This is particularly important when it is desired to plot trajectories for barrage warfare. For this purpose we have provided two positively acting adjustable stops 80 which are so mounted as to limit the movement of the cradle about the axis of the pivot pin 14. We have found it convenient to utilize one of the links, as for instance the link 46, as a means for supporting these stops. As illustrated, there are two stops 51 and 52 which are longitudinally adjustable along the link 46. The link is provided with an undercut longitudinal groove 53 which receives tongues (not shown) on the stops and thus guides the stops for longitudinal movement. The stops 51 and 52 are adapted to be engaged by the head 48^a on the bolt 48 and it will be obvious that the engagement of the said head with one of the stops limits any further movement of the cradle. Each of the stops is provided with a thumb screw 54 by means of which it may be clamped in position and preferably the upper surface of the link 46 is serrated to facilitate clamping. A screw 55 is preferably provided which serves as a means for preventing the stops from being accidentally removed from the link.

What we claim is:

1. In a gun mount, the combination of ground engaging legs, a cradle supported by the legs, means for detachably supporting a gun on the cradle so as to permit longitudinal sliding movement of the said gun during bodily recoil thereof, means carried for the cradle for adjusting the elevation of the gun with respect to the said cradle, the said means being arranged to freely permit the aforesaid longitudinal movement of the gun, 110 and a spring connected with the cradle and adapted for resisting longitudinal movement of the gun in the recoil direction.

2. In a gun mount, the combination of ground engaging legs, a cradle supported by the legs, a saddle carried by the cradle and longitudinally slidably thereon, means whereby a gun may be detachably secured to and solely supported by the saddle, the slidable mounting of the saddle permitting it to move 125 longitudinally with the gun during bodily recoil thereof, means carried by the cradle for angularly adjusting the saddle with respect to the said cradle and thereby changing the elevation of the gun, the said means 130

permitting the free longitudinal movement of the saddle and gun as aforesaid, and a spring connected with the said cradle and saddle for resisting longitudinal movement of the latter in the recoil direction.

3. In a gun mount, the combination of ground engaging legs, a cradle supported by the legs and comprising two parallel normally vertical spaced side plates, a saddle positioned between the side plates of the cradle and having longitudinal grooves in the side portions thereof adjacent the respective side plates, shoes carried by the side plates and fitting the grooves to guide the saddle for longitudinal movement, means whereby a gun may be detachably secured to and solely supported by the saddle, the mounting of the saddle permitting it to move longitudinally with the gun during bodily recoil thereof, and a spring connected with the said cradle and saddle for resisting longitudinal movement of the latter in the recoil direction.

4. In a gun mount, the combination of ground engaging legs, a cradle supported by the legs and comprising two parallel normally vertical spaced side plates, a saddle positioned between the side plates of the cradle and comprising two parallel side plates respectively adjacent the side plates of the cradle and respectively provided with longitudinal grooves in their outer faces, shoes carried by the side plates of the cradle and fitting the said grooves to guide the saddle for longitudinal movement, means whereby a gun may be detachably secured to and solely supported by the saddle, the mounting of the saddle permitting it to move longitudinally with the gun during bodily recoil thereof, and a spring connected with the said cradle and saddle for resisting longitudinal movement of the latter in the recoil direction.

5. In a gun mount, the combination of ground engaging legs, a cradle supported by the legs and comprising two parallel normally vertical spaced side plates, a saddle positioned between the side plates of the cradle and having longitudinal grooves in the side portions thereof adjacent the respective side plates, shoes carried by the side plates and fitting the grooves to guide the saddle for longitudinal movement, means whereby a gun may be detachably secured to and solely supported by the saddle, the mounting of the saddle permitting it to move longitudinally with the gun during bodily recoil thereof, means for adjusting the shoes relatively to the cradle to angularly move the saddle and thereby change the elevation of the gun, and a spring connected with the said cradle and saddle for resisting longitudinal movement of the latter in the recoil direction.

6. In a gun mount, the combination of

ground engaging legs, a cradle supported by the legs and comprising two parallel normally vertical spaced side plates, a pin and a yoke extending transversely between the said side plates, a saddle positioned between the side plates of the cradle and comprising two parallel side plates respectively adjacent the side plates of the cradle, the last said side plates being longitudinally slotted to receive the pin and the yoke and also being respectively provided with longitudinal grooves in their outer faces adjacent the slots, shoes carried by the pin and the yoke respectively and fitting the said grooves to guide the saddle for longitudinal movement, means whereby a gun may be detachably secured to and solely supported by the saddle, the mounting of the saddle permitting it to move longitudinally with the gun during bodily recoil thereof, means for vertically adjusting the yoke and the shoes carried thereby to angularly move the saddle about the pin and thereby change the elevation of the gun, and a spring connected with the said cradle and saddle for resisting longitudinal movement of the latter in the recoil direction.

7. In a gun mount, the combination of ground engaging legs, a cradle supported by the legs and comprising two parallel normally vertical spaced side plates, a pin and a yoke extending transversely between the said side plates, a saddle positioned between the side plates of the cradle and comprising two parallel side plates respectively adjacent the side plates of the cradle, the last said side plates being longitudinally slotted to receive the pin and the yoke and also being respectively provided with longitudinal grooves in their outer faces adjacent the slots, shoes carried by the pin and the yoke respectively and fitting the said grooves to guide the saddle for longitudinal movement, means whereby a gun may be detachably secured to and solely supported by the saddle, the mounting of the saddle permitting it to move longitudinally with the gun during bodily recoil thereof, means for vertically adjusting the yoke and the shoes carried thereby to angularly move the saddle about the pin and thereby change the elevation of the gun, and a coil spring connected at one end with the saddle and at the other end with the yoke and serving to resist longitudinal movement of the saddle in the recoil direction.

8. In a gun mount, the combination of ground engaging legs, a cradle supported by the legs, a saddle carried by the cradle and longitudinally slidably thereon, means whereby a gun may be detachably secured to and solely supported by the saddle, the slidably mounting of the saddle permitting it to move longitudinally with the gun during bodily recoil thereof, means carried by

the cradle for angularly adjusting the saddle with respect to the said cradle and thereby changing the elevation of the gun, the said means permitting the free longitudinal movement of the saddle and gun as aforesaid, a spring connected with the said cradle and saddle for resisting longitudinal movement of the latter in the recoil direction, and a second spring also connected with the 5 said cradle and saddle for limiting longitudinal movement of the latter in the return or counter-recoil direction.

9. In a gun mount, the combination of ground engaging legs, a cradle supported by the legs and comprising two parallel normally vertical spaced side plates, a pin and a yoke extending transversely between the said side plates, a saddle positioned between the side plates of the cradle and comprising 10 two parallel side plates respectively adjacent the side plates of the cradle, the last said side plates being longitudinally slotted to receive the pin and the yoke and also being respectively provided with longitudinal grooves in their outer faces adjacent the slots, shoes carried by the pin and the yoke respectively and fitting the said grooves to guide the saddle for longitudinal movement, means whereby a gun may be detachably secured to and solely supported by the saddle, the mounting of the saddle permitting it to move longitudinally with the gun during bodily recoil thereof, means for vertically adjusting the yoke and the shoes carried thereby to angularly move the saddle about the pin and thereby change the elevation of the gun, and two opposed coil springs connected at their outer ends with the saddle and at their inner ends with the yoke, one 20 spring serving to resist longitudinal movement of the saddle in the recoil direction and the other serving to limit longitudinal movement of the saddle in the return or counter-recoil direction.

45 10. In a gun mount, the combination of ground engaging legs, a cradle supported by the legs, a saddle carried by the cradle and longitudinally slidably thereon, means whereby a gun may be detachably secured to and solely supported by the saddle, the slid- 50 able mounting of the saddle permitting it to move longitudinally with the gun during bodily recoil thereof, means carried by the cradle for angularly adjusting the saddle with respect to the said cradle and thereby changing the elevation of the gun, the said means permitting the free longitudinal movement of the saddle and gun as aforesaid, a spring connected with the said cradle and saddle for resisting longitudinal movement of the latter in the recoil direction, and a spring connected between the cradle and the saddle for applying vertical pressure to the latter and thereby preventing lost motion of the saddle with respect to the cradle. 60

11. In a gun mount, the combination of ground engaging legs, a pivot base carried by the legs, a swivel base mounted on the pivot base, the said pivot base and swivel base being provided respectively with complemental pivot and bearing portions which adapt the swivel base for movement about a normally vertical axis and the said pivot base and swivel base being further provided respectively with complemental segmental bearing surfaces concentric with the said axis and supplemental to and spaced from the said pivot and bearing portions, a cradle carried by the swivel base above the segmental bearing surface thereof, two laterally spaced adjustable braces extending between the rear part of the cradle and the portion of the base adjacent the segmental bearing surface thereof, and means carried by the cradle for supporting a gun in position for firing. 70

12. In a gun mount, the combination of ground engaging legs, a cradle carried by the legs and pivoted for movement about a normally horizontal axis, means carried by the cradle for supporting a gun in position for firing, two links at opposite sides of the cradle each having one end horizontally pivoted to the swivel base below the cradle, means on the cradle engaging the links and permitting them to slide lengthwise when the cradle is adjusted about the said horizontal axis, and a single means for locking both of the links in fixed relation to the cradle whereby the links serve as supporting braces. 80

13. In a gun mount, the combination of ground engaging legs, a pivot base carried by the legs, a swivel base mounted on the pivot base, the said pivot base and swivel base being provided respectively with complemental pivot and bearing portions which adapt the swivel base for movement about a normally vertical axis and the said pivot base and swivel base being further provided respectively with complemental segmental bearing surfaces concentric with the said axis and supplemental to and spaced from the said pivot and bearing portions, a cradle carried by the swivel base about the segmental bearing surface thereof, the said cradle being pivoted to the said swivel base for movement about a normally horizontal axis located near the aforesaid vertical axis, means carried by the cradle for supporting a gun in position for firing, a link having one end horizontally pivoted to the swivel base near the segmental bearing surface thereof, means on the cradle engaging the link and permitting it to slide longitudinally when the cradle is adjusted about the said horizontal axis, and means for locking the link in fixed relation to the cradle whereby the link serves as a supporting brace. 105

110

115

120

125

130

14. In a gun mount, the combination of ground engaging legs, a cradle supported by the legs and pivoted for movement about a normally horizontal axis, means carried by the cradle for supporting a gun in position for firing, and two positively acting adjustable stops for limiting the movement of the cradle about the said horizontal axis.
- 10 15. In a gun mount, the combination of ground engaging legs, a cradle carried by the legs and pivoted for movement about a normally horizontal axis, means carried by the cradle for supporting a gun in position 15 for firing, a link having one end horizontally pivoted to the swivel base below the cradle, means on the cradle engaging the link and permitting it to slide lengthwise when the cradle is adjusted about the said 20 horizontal axis, and two positively acting stops adjustably mounted on the link for

limiting the movement of the cradle about the said horizontal axis.

16. In a gun mount, the combination of ground engaging legs, a cradle carried by the legs and pivoted for movement about a normally horizontal axis, means carried by the cradle for supporting a gun in position for firing, a link having one end horizontally pivoted to the swivel base below the 25 cradle, means on the cradle engaging the link and permitting it to slide lengthwise when the cradle is adjusted about the said horizontal axis, two positively acting stops 30 adjustably mounted on the link for limiting the movement of the cradle about the said horizontal axis, and means for locking the link in fixed relation to the cradle whereby the link serves as a supporting brace.

FREDERICK T. MOORE.
CHRISTIAN PFEIFFER.
